Examiner's Report of Canadian Patent Application for Registration of an Industrial Design, dated Jun. 30, 2016.

Primary Examiner — Anhdao Doan(74) *Attorney, Agent, or Firm* — Knobbe Martens Olson & Bear LLP(57) **CLAIM**

The ornamental design for a human body safety inspection instrument, as shown and described.

DESCRIPTION

FIG. 1 is a first perspective view of a human body safety inspection instrument, showing our new design.

FIG. 2 is a second perspective view thereof.

FIG. 3 is a right side elevational view thereof.

FIG. 4 is a left side elevational view thereof.

FIG. 5 is a front elevational view thereof.

FIG. 6 is a rear elevational view thereof; and,

FIG. 7 is a top plan view thereof.

The broken lines shown in FIGS. 1-2 and 5-6 illustrate optional surface ornamentation for the human body safety inspection instrument that forms no part of the claimed design. A bottom plan view of the human body safety inspection instrument is not normally seen during use and forms no part of the claimed design, has therefore been omitted.

1 Claim, 7 Drawing Sheets(56)
